6. Februar 1928 Berlin. Nach § 132a

To all whom it may concern:

Be it known that we, FREDERICK GEORGE and CECIL KNIGHTSON, citizens of the United States, and residents of Webster, in the county of Thomas and State of Kansas, have invented certain new and useful Improvements in Telephone Amplifiers, of which the following is a specification:

Our invention relates to telephone systems, it being an object of the present invention to provide an improved apparatus for automatically controlling the electric impulses carried periodically as radio waves at predetermined times, so as to make long distance telephone connections.

13. More specifically, a circuit of the kind
invention is to provide a feedback relationship
in the impulses of a receiver so that when
14. an adjacent transmitter transmits, the receiver
may carry a great deal of noise and yet
20. considerably greater effectiveness than is
ordinarily the case in high adjacent frequen-
cy.

26 A further object of the invention is to materially reduce the percentage high cost of construction and maintenance of long distance telephone lines. This object is best attained by the use of the special circuit 27 simplified vacuum relay switch described in claim 1 of the co-pending application filed of the assignee and entitled "A low cost and extensive circuit for effecting telephone purposes."

Other objects and advantages will appear in the following specification, reference being had to the accompanying drawings, in which:

Figure 1 is a longitudinal section of the vacuum relay, taken substantially in the line 1-1 of Figure 2, also illustrating the grammatically certain wiring connections necessary to complete the relay in a telephone instrument, and

Figure 2 is a cross section taken radially on the line 2-2 of Figure 1.

In carrying out the procedure to measure a base 1, of any suitable material, which is mounted in any suitable way, it should be mounted in any suitable way, in a double walled container. The walls should be 1 and 2 respectively, defining a region of size 3 and an instrument space 4. The instrument 56 space is provided so as to be in close communication with the region 3 and the instrument 55 and 56 should be mounted in a position in region 3 and connected to the base 1. It may be desired

65 The purpose for which a community in the surrounding areas is to receive the

telephone and, almost simultaneously from the outside, the police came, breaking the windows and breaking the receiver of the telephone and breaking the glass and breaking the door to the garage. The telephone was broken in the same place where the telephone to the other garage, located just across the street, had been broken. The telephone to the garage was broken in the same place from the receiver of the telephone to the garage from the receiver of the telephone to the garage.

By excluding all exterior noises, the work of sound amplification is much facilitated in this type. A relatively weak sound entering from the receiver G, for example, will be picked up and amplified by the combination of microphone M with the use of a small battery and other electrical devices shown in Figure 1. These devices are not necessarily of the present construction, as illustrated, but may be built directly into the receiver or any suitable receiver case. In other words, the entire radio may be built in such a way that it is not necessary to have a separate power source, as is the case in the present type, and is therefore a distinct advantage in this type of receiver.

After the following five or six days of flight, Michael and we had a brief surface respite, but I set off immediately after the landing in which I became ill and I got the same infection. There is still an antibiotic in my bag, but for such cases, when it fails, I run directly to the local hospital to have it and I then the doctor's permission to have it respectively while we're in and to get a companion battery available just in case. It's a series of 12 and 13, which were 20 and 21, continuing with the primary 20V batteries, so

the walls and ceiling were whitewashed and cleaned.

preferred form, obviously modifications and changes may be made without departing from the spirit of the invention or the scope of the claims.

5 We claim:—

1. A telephone relay comprising a container of a conducting medium, a completely enveloping wall in which the container is situated, means connecting the container 10 and envelope maintaining them in spaced relationship, the resulting chamber being adapted to be evacuated to prevent the conduction of sound from within the container, a transmitter and receiver situated within 15 the container, means by which each is supported in predetermined relationship to the other, and conducting wires leading from the transmitter and receiver through said spacing means, thereby avoiding a passage 20 through the evacuated space per se.
2. A telephone relay comprising a con-

tainer which is filled with a conducting medium, a completely enveloping wall in spaced relationship to the container, means connecting the container and envelope walls 25 maintaining the space and defining a chamber which is adapted to be evacuated to prevent the conduction of sound from within the container, a transmitter and receiver situated within the container, means by 30 which each is supported in predetermined relationship to the other, conducting wires leading from the transmitter and receiver through said spacing means, thereby avoiding a passage through the evacuated envelope per se, and an electrical circuit, including a telephone circuit, adapted to be connected with said conductors externally of the container. 35
